(57) **CLAIM**

The ornamental design for a tape measure truck, as shown and described.

DESCRIPTION

FIG. 1 is a front elevational view of a tape measure truck showing my new design;

FIG. 2 is a left side elevational view thereof, the right side elevational view being a mirror image thereof;

FIG. 3 is a top plan view thereof;

FIG. 4 is a bottom plan view thereof;

FIG. 5 is a rear elevational view thereof; and,

FIG. 6 is a rear perspective view thereof, the broken lines showing a tape measure being included for the purpose of illustrating environmental elements only and forming no part of the claimed design.
